(57) CLAIM

The ornamental design for a worksurface as shown and described.

DESCRIPTION

FIG. 1 is a side view of a first embodiment of a worksurface, with the opposite side view being a mirror image thereof; FIG. 2 is a first end view of the worksurface shown in FIG. 1;

FIG. 3 is a second end view of the worksurface shown in FIG. 1 opposite the first end view;

FIG. 4 is a top view of the worksurface shown in FIG. 1; FIG. 5 is a bottom view of the worksurface shown in FIG. 1;

FIG. 6 is a top perspective view of the worksurface shown in FIG. 1;

FIG. 7 is a bottom perspective view of the worksurface shown in FIG. 1;

FIG. 8 is a side view of a second embodiment of a worksurface, with the opposite side view being a mirror image thereof;

FIG. 9 is a first end view of the worksurface shown in FIG. 8;

FIG. 10 is a second view of the worksurface shown in FIG. 8 opposite the first end view;

FIG. 11 is a top view of the worksurface shown in FIG. 8; FIG. 12 is a bottom view of the worksurface shown in FIG. 8;

FIG. 13 is a top perspective view of the worksurface shown in FIG. 8; and,

FIG. 14 is a bottom perspective view of the worksurface shown in FIG. 8.

The broken lines in the drawings depict environment and form no part of the claim.

1 Claim, 9 Drawing Sheets
